COMMERCIAL PACKAGE

Hollis J. Quinlan, East Cleveland, Ohio, assignor
of one-half to Herbert Stratford, Cleveland,
Ohio

Application July 24, 1936, Serial No. 92,405

3 Claims. (Cl. 206—29)

This invention relates to a commercial package, and particularly to book matches or the like which are used for advertising purposes.

It has been found that ordinary book matches, 5 of the paper-cover type, have been very effective as a medium of advertising. These match books are distributed indiscriminately over large areas, and thereby come into the possession of many people who may be interested casually in the subject matter of the advertising they contain. One difficulty arises, however, in that the person interested in such advertisement will not be stimulated to investigate the subject of the advertisement further, unless the means for doing so are 10 conveniently accessible. On the other hand, many business houses have found that a self-addressed business reply card has been very effective in obtaining replies from people who are interested in products that have been widely advertised. In this manner of doing business, the 15 person solicited is not required to do anything except indicate his desire for further information on the subject matter which constitutes the advertisement. As the business reply card is self-addressed, it is only necessary for the person into whose possession it comes, to subscribe his name and address thereon, so that the information may be mailed to him directly or be delivered by personal contact.

Having in mind the wide circulation of the ordinary match book, and also the effectiveness of the business reply card, it is therefore the primary object of my invention to bring these two media of advertising effort together in the large 20 field of distribution covered by the ordinary match booklet.

It is a further object of my invention to combine a business reply card with a book of matches to form an article which can be manufactured 25 in large quantities at a small cost, and which will not lose the desired compactness of commercial match books now in use.

A further object is to provide a combined match book cover and postal card in such manner as to 30 conform with the standards of match book manufacture and postal department requirements.

Further and more specific objects of my invention will appear from the following description 35 given in connection with the accompanying drawing, where Fig. 1 is a perspective view of a match book, illustrating my invention; Fig. 2 is a centrally located section, taken along the line 2—2 in Fig. 1; Fig. 3 is a plan view of a business reply 40 card used in connection with my invention; Fig.

4 is a plan view of a folded card, with a match strip secured thereto; Fig. 5 is a plan view of the reply card, after being detached from the match strip for mailing, and Fig. 6 is a plan view of a business reply card, illustrating another form of 5 my invention.

Referring now to Figs. 1 and 2, I have shown a match book having a strip of matches 1, a cover 2, and a back 3. A portion of the back is doubled around the base of the match strip to 10 form the striking surface 4, and is secured to the match strip and the back by means of a staple 5 in the well-known manner.

In Fig. 3 I have illustrated a business reply card 15 6 which is used to form the cover, back and striking surface respectively of the match book. I have found that for this purpose, a business reply card which will meet the postal regulations as to size, can be utilized to advantage in that when it is folded once lengthwise, the doubled portion will 20 be of sufficient width to cover the ordinary match strip of commercial match books, which are now in use. It is advantageous from a manufacturing standpoint to fold the cover to a standard width, so that commercial machinery now in use 25 may be readily adapted to assemble my invention in large production quantities. The card 6, as illustrated in Fig. 3, contains the return address on the upper side 7 and suitable advertising material on the reverse side 8. A tab 9 is formed on 30 one end of the card, to provide sufficient area for the striking surface 4, after the same has been doubled around the base of the match strip 1. In the forms shown in Figs. 3 and 4, the tab 9 is 35 cut so that it is only one-half of the width of the card, and may be disposed adjacent either the top or bottom edge thereof. Perforations are provided along the line 10, so that the card may be easily detached after the tab has been secured to the match strip.

As illustrated in Fig. 4, the card is folded so that the edge 15 will overlie the edge 16, thereby placing the return address on the side 7 within the fold and the advertising material on the outside thereof. The match strip 1 is then secured 45 to the tab 9 by means of the usual staple 5. When the match book is thus assembled, the card may be unfolded for observation without detaching the same from the match book, as illustrated by the broken lines in Fig. 4.

In order to detach the advertising material appearing on the outside cover of the match book, it is only necessary to tear it from the match strip along the perforated line 10. The party desiring this information may then subscribe 50 55

his name and address on the back of the card 8, as illustrated in Fig. 5, and request any other information which he desires to be sent to him by return mail.

5 While I have shown in the drawing the type of advertising in which the party interested merely checks one of the items, about which he is seeking information, my invention may be adapted for use in any type of advertising. The card 10 6, when unfolded, is of sufficient size to meet the postal requirements of business reply cards, and should not be less than two and three-fourths inches wide by four inches long, when detached. The card also possesses greater space for carrying 15 advertising material which is not available on commercial match books now in use. Other forms of my invention may include return information on cards or letters of various sizes, but the postal reply card is the most satisfactory 20 because it is self-addressed with postage paid.

To facilitate production of match books in large quantities, I have adapted another form of my invention as illustrated in Fig. 6. The tab 9 and the perforations 10 are disposed across 25 the entire width of the card. Thus, when the card is folded lengthwise, the perforations will overlie one another. The card may then be detached from the match strip in the same manner as before described, that is, by tearing it 30 along the perforations 10, which are now doubled.

The cards illustrated in Figs. 3 and 6, may be cut either individually or remain in a continuous strip, depending upon the machinery which is used for assembling the match book. By 35 the latter method, the card may be printed and perforated before entering the match book machine. Thereafter, the continuous strip may be folded and the match strip applied and stapled, to be followed by the cutting off operation.

40 It may thus be seen that I have invented a new and useful advertising device, which will take advantage of the extensive circulation of the commercial match books now in use, and combine therein the qualities of the business reply card or other return information in soliciting 45 replies from people who are interested in such advertising material.

It should be understood that while I have shown the embodiment of my invention in the form of a match book, nevertheless the same can be utilized in connection with the distribution of various articles of commerce which are either being sold or given away to feature advertising matter, such as tooth picks, golf tees

and other utilitarian articles, which are adaptable to packaging in match-book form.

I claim:

1. A commercial package comprising a strip of detachable merchandise, a cover for said merchandise formed of a postal reply card folded into a double form whereby a single fold is produced in the card and the width of the package is one-half of the open card, and one end of said form being extended around the base portion of the strip, a staple for securing the cover to the strip, and said folded cover having a series of perforations disposed in both thicknesses thereof and located above the staple to facilitate removal of the cover from the strip, without tearing the same so that it may be unfolded and be returned through the mails. 5

2. A commercial package comprising a strip of detachable merchandise, a cover for said merchandise formed of a card folded into a double form whereby a single fold is produced in the card and the width of the package is one-half of the open card, a tab projecting outwardly from one end of one leaf of the folded cover and extending across one half of the width of the card when unfolded, a staple for securing the tab to the base of the strip, and said folded cover having a series of perforations disposed along the line adjoining the tab to the card and above the point of attachment of the staple, to facilitate removal of the cover from the strip after the merchandise has been detached, without tearing the same so that it may be unfolded and be returned through the mails. 20

3. A commercial package comprising a flexible generally rectangular sheet folded on a median line to bring two of its edges together, said sheet having a foldable extension at one end joined thereto by a weakened line, a strip of merchandise having one end thereof embraced within a fold of said extension and its other end embraced within a fold of the double sheet formed transversely to the median line aforesaid, a staple passing through the end of the strip embraced by the extension and through both thicknesses of the extension beyond the weakened line aforesaid, whereby to facilitate affixing the strip to the cover by the staple and removal of the cover from the strip along the weakened line without mutilating the cover, and the cover being of such size and shape as to be transmittable through the mail when detached from the merchandise and unfolded to its flat condition. 35 40 45 50
